UNITED STATES PATENT OFFICE.

GUY B. WAITE, OF NEW YORK, N. Y.

ANTISLIPPING DEVICE FOR AUTOMOBILE-TIRES.

1,329,483.

Specification of Letters Patent.

Patented Feb. 3, 1920.

Application filed June 4, 1917. Serial No. 172,801.

To all whom it may concern:

Be it known that I, GUY B. WAITE, a citizen of the United States, residing at New York, in the county of New York and 5 State of New York, have invented certain new and useful Improvements in Antislipping Devices for Automobile-Tires, of which the following is a specification.

This invention relates to improvements in 10 anti-slipping devices for automobile tires and has for its object to provide a device which is simple in construction, durable, and effective in operation.

This improvement relates to that character 15 of anti-slipping devices which lie transversely across the tread of the tire and are spaced from each other around the tire, and retained in position by any suitable means secured to or positioned on opposite sides 20 of the wheel.

One of the particular objects of the invention, is to provide a type of transverse member which embodies a compressible anti-slipping traction element and a rigid casing 25 or holder for inclosing the same, and by which the anti-slipping traction element is secured in position.

These and other objects hereinafter set forth, are attained by the means illustrated 30 in the accompanying drawing, in which:—

Figure 1 is a perspective view of one of the transverse members.

Fig. 2, is a side elevation of a portion of a tire (shown in dotted lines) showing several 35 of the transverse members in position.

Fig. 3, is a plan view of one of the transverse members.

Fig. 4, is a cross-section on the line 4—4 of Fig. 3.

Fig. 5, is a longitudinal section of one end 40 of one of said members.

Fig. 6, is a plan view of a blank from which the casing or holder is formed, and Fig. 7, is a view of a modified form of casing.

Similar reference numerals in all of the figures of the drawing designate like parts.

The preferred form of the anti-slipping element of each of the transverse members, 50 consists of a plug or pad 10 made up of a plurality of layers of fabric material known in the trade as friction or frictional fabric, and which is constructed of suitable canvas provided with a coating of rubber.

55 The layers of the fabric are united in the usual manner, preferably by vulcanizing,

and the pad thus formed is then cut to the desired size and shape for the purpose intended. The pad is used in this invention in a manner to present the edges of the fabric 60 on one side of the pad to the roadway, and as thus positioned, the edges of the fabric engage the roadway with sufficient friction to prevent slipping.

In the practical use of the pad constructed 65 and presented to the roadway as above described, it has been found that the pressure imposed upon the pad has a tendency of spreading the same in all directions, so that it has been necessary to provide a rigid 70 holder or casing for the pad which will completely confine and inclose all sides, including the bottom of the pad, only excepting the side or surface which is to engage the roadway.

The preferred form of holder is clearly 75 shown in Fig. 1 of the drawing, and the same is constructed from a blank of flat metal of the form shown in Fig. 6. The blank is cut rectangular in shape, with 80 rounded corners, and notched at 11 to partly form the ears 12, which are apertured at 13, to receive the connections 14, after the blank has been folded to its final shape.

Pad 10 is preferably formed to the shape 85 disclosed by the dotted lines at 15 in Fig. 6, so that when the sides of the blank are folded at an angle to the bottom on the dotted lines 16, the ends of the blank will form 90 the ears 12 when brought together in close contact, thereby forming double ears.

This manner of folding or compressing the blank around the compressible anti-slipping pad firmly incloses the same excepting the tread surface, so that, when pressure is 95 imposed upon the pad in running over the roadway, it is compacted within the holder forming an almost solid mass.

It has been discovered in practical use, 100 the pad will pick up sand and other gritty materials from the roadway, and as the pad is being compressed within its holder, the gritty materials will become firmly embedded and serve to further add to the efficiency of the anti-slipping element.

105 Preferably when the device is first formed, the pad is thick enough to project slightly above the upper edges of the inwardly inclined sides of the holder, so that, when it is compressed, the holder will be compactly and completely filled. It is understood that the holder is tightly clamped

around the pad, sufficiently to prevent the pad from being accidentally displaced, and as a further precaution to prevent the loss of the pad, the top edges 17 of the holder 5 adjacent the ears 12, are slightly pressed inwardly over the ends of the pad, as clearly shown in Fig. 3 of the drawing.

The holder is preferably slightly curved longitudinally, as shown at 18 in Figs. 1 10 and 5, so that only a short length of the holder will normally rest upon the tread of the tire. This slight curvature will allow the tire to flatten on compression and without pressing against the ends of the holder, 15 which would happen should the holder be curved to conform to the tire. The holder is partially flat on its bottom and has rounded lower longitudinal edges 19, forming a substantially convex bottom as seen clearly 20 in the cross-section shown in Fig. 2 of the drawing. This particular formation not only provides a flat seat for the holder upon the periphery of the tire, but at the same time the rounded edges will allow the holder 25 to tilt without danger of cutting the tire.

As thus constructed, it will be seen, that a simple construction is provided which will 30 form a holder that will clamp and retain a compressible anti-slipping pad, and which is formed from a blank of flat metal whose opposite sides at the ends are pressed into contact with each other to form the closed ends of the complete holder and its double ears.

35 To retain the transverse members in position around the tire, a flexible connection is secured to the ears of holder at each end, each of said connections preferably comprising a link 20 and a link hook 21, said hook 40 being adapted to engage the usual type of chain supports 22 that are positioned on both sides of the wheel. Links 20 are adapted to loosely engage through the apertures 13 of the holder, so that the holder is free to tilt 45 in either direct or transversely, or rock longitudinally. Preferably these links 20 are closed by welding to prevent their accidental displacement or removal by the shock and strains imposed as the transverse members 50 strike the roadway. The sealed links also prevent the separation of the ends or ears under undue strains, it being understood that the inherent qualities of the metal used for forming the holders is such, that it can 55 not be bent without considerable force.

The modified form shown in Fig. 7 is primarily formed by casting, it also being understood that the same is formed with suitable bendable material which can be clamped 60 tightly upon the anti-slipping pad.

Having thus fully described the invention, what is claimed is:—

1. A transverse member of the class described, comprising a holder formed from a 65 blank of sheet-metal bent longitudinally ad-

jacent its ends to provide end-walls and vertically disposed attaching ears, said blank also having its side-edges bent outwardly to form inclosing sides, and an anti-slipping pad positioned between said sides and 70 clamped in position by said end-walls.

2. A transverse member of the class described, comprising a holder formed from a blank of sheet-metal bent longitudinally adjacent its ends to provide end-walls and 75 vertically disposed attaching ears, said blank also having its side-edges bent outwardly to form inclosing sides, and an anti-slipping pad positioned between said sides, said end-walls having their outer edges bent inwardly to clamp said pad in position.

3. A transverse member of the class described, comprising a holder formed from a blank of sheet-metal bent longitudinally adjacent its ends to provide end-walls and 80 vertically disposed ears, said blank also having its side-edges bent outwardly to form inclosing sides, said inclosing sides being inclined toward each other, and an anti-slipping pad seated in the holder between the 85 walls thereof and retained in position by said inclined sides.

4. A transverse member of the class described, embodying a holder formed of bendable metal and having a solid bottom, 90 and closed side and end walls, said end walls also forming attaching ears, and a compressible and compactible anti-slipping pad seated in said holder and being clamped therein by said walls, said end walls being 95 formed by extending said side walls around the ends of said pad and also extending them outwardly from their point of contact with each other adjacent to the ends of the pad to form the attaching ears. 100

5. A transverse member of the class described, embodying a holder formed of bendable metal and having a solid bottom, and closed side and end walls, said end walls also forming attaching ears, and a compressible and compactible anti-slipping pad seated in said holder and being clamped therein by said walls, said end walls being partially bent over upon the top of the pad and being formed by extending said side walls 110 around the ends of said pad and also extending them outwardly from their point of contact with each other adjacent to the ends of the pad to form the attaching ears. 115

6. In a transverse member of the class described, an anti-slipping pad holder formed from a blank of sheet metal, and which is bent longitudinally and centrally at its ends to provide end walls and attaching ears, and also bent longitudinally on two lines parallel with its side edges and intermediate its ends to provide side walls and a bottom. 120

In testimony whereof I affix my signature.

GUY B. WAITE.
